UNITED STATES PATENT OFFICE.

EDWARD DUFFY, OF PAWTUCKET, RHODE ISLAND.

PLUMB-LEVEL.

SPECIFICATION forming part of Letters Patent No. 360,378, dated March 29, 1887.

Application filed November 8, 1886. Serial No. 218,227. (No model.)

To all whom it may concern:

Be it known that I, EDWARD DUFFY, of the city of Pawtucket, in the county of Providence and State of Rhode Island, have invented certain new and useful Improvements in Gravity-Levels, of which the following is a full, clear, and exact description, reference being had to the accompanying drawings, forming part of this specification.

10 This invention relates to a device or level for ascertaining the relative inclination or angle of a certain line or surface to a horizontal plane.

As is well known, the ordinary spirit and 15 plumb-line levels are awkward to use in some cases, and in many cases they are not suited for the work of finding certain angles and leveling. In this class of devices it is desirable to have a level that will be universally 20 adaptable and suited to find a level or horizontal line and the angularity of any line or surface to a horizontal plane, and that may be readily used in inconvenient situations, and that may have the indicating or registering 25 hand set or fixed at the position registered for subsequent reading and calculation.

The objects of my invention are to provide 30 a form of gravity-level that will be handy and fitted for all required work in ascertaining the relative inclination of any lines and surfaces to the horizontal plane, and that can be set at the registering-points for subsequent reading.

To the aforesaid purposes my invention consists, chiefly, in the employment of a pendulum-bar pivoted near the center thereof and of a dial having the degrees of a circle marked thereon for the pendulum-bar to register on, and of means for fixing the pendulum-bar against oscillation, and of other novel constructions and arrangements of the parts of the device, all as hereinafter fully described and claimed.

In the accompanying drawings, illustrating 45 my invention, Figure 1 represents a front elevation of my improved gravity-level arranged with a suitable frame, the lower part of the pendulum-bar being shown in broken lines. Fig. 2 represents a sectional view of the level,

taken on line 2 2 in Fig. 1, and showing the constructions and relative disposition of the 50 several features of invention.

In the said drawings like numbers of reference designate corresponding parts throughout.

Referring to the drawings, the frame 5 may 55 be of any suitable shape to properly support the parts of the device, and is provided with a flat base, 6, which is supposed to represent the horizontal plane in using the level. The frame 5 is formed with a cylindrical chamber, 60 7, having an open front. In the center of the back of chamber 7 is arranged the stop-screw 8, provided on the foot with the conical bearing-socket 9, and working in the screw-threaded 65 perforation 10 of the frame.

The rigid arm 11 is fixed upon the front of the frame by means of a set-screw, 12, and extends radially to about the center of the opening of the chamber 7, and is provided upon the back thereof with the conical bearing-socket 13, which is adjusted to lie opposite the bearing-socket 9 of the stop-screw 8.

The pendulum-bar 14 is provided near the center thereof with the fixed pivot 15, set normal to the plane of oscillation of the bar, and 75 provided with the conical ends or journal-centers 16 and 17, respectively, which are journaled in the bearing-sockets 13 and 9, respectively.

The lower end of the pendulum-bar 14 is 80 provided with a suitable weight, 18, formed somewhat crescent-shaped, and designed to give sufficient momentum to the bar in oscillating. The upper portion of the pendulum-bar, above the pivot 15, is made like an index-hand, 19, and is bent transversely on itself, in order to place the said upper and lower portions of the bar in parallel planes, as clearly indicated in Fig. 2, and the purpose of this construction is to permit the index-hand 19 to 85 lie to the front of, while the weighted end lies to the back of, the graduated dial 20, which is placed over the front of chamber 7, and is formed with the central eye, 21, disposed in alignment with the bearing-sockets 9 and 13. 90 The circular dial 20 is provided upon the front 95

face with the graduations of the degrees of a circle, beginning with zero at the top and running around each way in graduations of five degrees till ninety degrees are reached at diametrically-opposite points at the sides, and then beginning with these ninety-degree points as zero-points the graduations continue still uniform until the ninety-degree point is reached at the bottom of the dial, thus completing the circle and making the requisite sum total of three hundred and sixty degrees.

The dial-plate 20 is loosely set in the cut-away portion or depression 23, and the ring-plate 24 is placed over it and clamps it securely in adjusted position against displacement by means of the screws 25 being socketed in the frame 5. The glass plate 26 is mounted within the ring-plate 24, as shown, and serves to exclude the dirt from the works of the device. By virtue of the construction of the dial 20 being clamped in position by the removable ring-plate 24, the dial may be readily released and trued to the zero-point, and in this position may be securely set.

The pivot 15 is peculiarly mounted, as before described, in relation to the stop-screw 8, in order that the screw may serve to stop and fix the pivot against movement, and thereby stop the oscillation of the pendulum-bar when it is desired to set said bar at any point on the dial. This stop adjustment of the pendulum-bar secures the important advantage that when it is desired to preserve or keep the reading made by the index-hand on the dial the stop-screw may be easily turned to firmly hold the index-hand. In cases where the positions to work in are inconvenient or the under face of a surface is to be leveled, this stop adjustment becomes of great service. The graduations of the dial 20 may be changed from the way I show it, and may be arranged to read from zero up to three hundred and sixty degrees in consecutive order.

In place of the peculiar form of frame 5 here illustrated, the works of the level may be set in a rectangular block, as is the case in spirit-levels, and thereby have four flat surfaces at right angles to each other, and each of which may be used as a plane to work from, in a manner well known.

From the foregoing description of my level it will be readily seen that the device may be used for all kinds of work in the finding of relative angles of lines, or in adjusting a line or plane at an inclination equal to a given inclination; and, moreover, may be readily trued and set.

There may be various modifications made in the principal parts of my invention without, however, making a substantial departure from the spirit of the same, as herein described and claimed.

It is to be observed that by the use of the logarithmic table of tangents, together with the graduations on the dial of the level, and by knowing the length of the index-hand, a very

slight calculation will give the relative inclination of a given line or surface in terms of the index-hand, since such a value will be merely proportional to the ratio between the 70 said inclined line or surface and the horizontal. For instance, if the index-hand be one inch long and it registers forty-five degrees, the ratio of inclination will be one to one, or for one horizontal inch the given inclination will be 75 one vertical inch, and for two inches horizontal the inclination will be two inches vertical, and so on. Thus by an ordinary use of logarithmic tables my level can be used to give valuable information or data to work on. 80

It is obviously impracticable to put a scale of the tangential values upon the dial; but the calculations may be made from a table, as above described.

I disclaim, broadly, the use of a gravity 85 pendulum-bar swinging on a pivot set in adjustable bearings and provided with an index-hand moving over a graduated dial, and having means for setting said bar in a fixed position, for I am aware that such constructions 90 have heretofore been used.

Having thus described my invention, I claim as new and desire to secure by Letters Patent—

1. In a gravity-level, the combination of a pendulum-bar provided near the center with 95 a fixed pivot set normal to the plane of oscillation and provided with taper ends, a support-frame provided with a base, an arm having a bearing-socket formed thereon for one end of said pivot, a stop-screw formed on the 100 end remote from the head with a bearing-socket for the other end of said pivot, said screw mounted in the frame opposite the bearing-socket in said arm, the pivot journaled in the said bearing-sockets, substantially as described, whereby the stop-screw may be turned to tighten and loosen the play of the pivot-joints, and may be set to fix the pendulum-bar 105 in any position of its oscillation, for the purpose herein set forth. 110

2. In a gravity-level, the combination of a suitable support-frame provided with a cylindrical chamber having an open front and a closed back, a stop-screw formed with a conical bearing-socket in the end of its foot and 115 set through the center of the back of said chamber, a rigid arm extending partially across the front of said chamber and provided on the back with a conical bearing-socket disposed opposite the socket in said stop-screw, a graduated dial placed over the front opening of said chamber and provided with a central eye in alignment with the said bearing-sockets, a pendulum-bar having a pivot near the center, provided with conical ends which are journaled in the said bearing-sockets, respectively, a ring-plate mounted upon said support-frame over the dial and holding the dial in place, and a glass set in said ring-plate, all constructed substantially as and for the purpose 120 described. 125

3. The combination, with the frame 5, pro-

vided with the chamber 7, of the arm 11, provided with the conical bearing-socket 13, the stop-screw 8, provided with the bearing-socket 9, and set through the screw-threaded perforation 10, the graduated dial 20, having the central eye, 21, therein, the ring-plate 24, removably fixed upon the frame, and the glass 26, all constructed and arranged substantially as and for the purpose herein described.

In witness whereof I have hereunto set my hand.

EDWARD DUFFY.
